STABILIZING AND GUIDE APPARATUS FOR
LIFTER ROOF TANKS

Donald E. Larson, Eureka, Calif., assignor to Chicago Bridge & Iron Company, a corporation of Illinois

Application July 31, 1946, Serial No. 687,408

6 Claims. (Cl. 48—176)

1

This invention relates to a lifter roof tank, and particularly to a stabilizing and guide apparatus for a lifter roof tank.

Lifter roof tanks comprise a shell and a lifter roof thereover designed to rise and fall with increasing and decreasing pressure within the tank. The tanks are designed for the storage of gas or mixtures of liquid and gas, and are provided either with a flexible sealing member between the shell and the roof or a liquid trap between the shell and the roof to prevent escape of the stored gases. When flexible sealing members are used this is ordinarily known as a dry seal. The flexible sealing member is ordinarily a fabric impregnated with a flexible impervious material such as synthetic rubber.

With tanks of this type it is ordinarily necessary that means be provided for guiding a roof during its travel and for stabilizing the roof so that unequal loads will not cause tipping of the roof. Various stabilizing and guide means have been proposed, but not all of these have been entirely satisfactory. It is also common practice to provide safety release valves, gauges, and other equipment with these tanks.

In the present invention improved stabilizing and guide means have been provided, with these means broadly comprising a plurality of substantially parallel depending arms rotatably attached at their upper ends to the roof, with each arm rotatably attached at its lower end to a longitudinally movable elongated member. Each elongated member is arranged adjacent the shell and has the shape of a section of a helix, with all elongated members being at substantially the same acute angle with respect to the horizontal, and all extending in the same direction. Guide members are provided on the shell for guiding each of the elongated members in its longitudinal path. There are also provided guide means between the roof and the shell for preventing rotation of the roof as it rises and falls.

The invention will be described as related to the embodiment shown in the accompanying drawings. Of the drawings Fig. 1 is an elevation of a lifter roof tank embodying the invention with the roof in its highest position; Fig. 2 is a view similar to Fig. 1 with the roof in its lowest position; Fig. 3 is a fragmentary plan view of the tank with portions broken away for clarity of illustration; and Fig. 4 is a vertical section taken along line 4—4 of Fig. 3.

The lifter roof tank shown in the accompanying drawings comprises a shell 10, a lifter roof 11 thereover, a depending skirt 12 attached to

2

the roof around the outer edge thereof and extending beyond the shell 10, and a flexible sealing member 13 extending between the skirt 12 and the top of the shell 10.

Spaced around the bottom of the skirt 12 are a plurality of horizontal brackets 14 extending inwardly, with their ends adjacent the shell 10 and supported by diagonal braces 15. On each bracket 14 there is located downwardly extending arm 16 having its top end rotatably attached to the bracket through depending plates 17 and a pin 18. The bottom end of each depending arm 16 is rotatably attached to a horizontal rod 19 passing through a hole at the lower flattened end 20 of the arm 16. Around the shell of the tank, but spaced therefrom, there is located a structural member 21 formed of straight lengths of pipe having their ends coupled together by couplings 22 to form a regular polygon. Each horizontal rod 19 has its outer end attached to a coupling 22 at the apex of the polygon.

On the inner end of each horizontal rod 19 there is located a longitudinally movably elongated member 23 arranged at an angle of approximately 45° with respect to the horizontal, with all said members extending in the same direction around the tank. Each structural member has the shape of a section of a helix and is of channel cross-section having inner edges 24 extending toward each other but separated to form an elongated slot. Mounted within each channel 23 is a top roller 25 and a bottom roller 26. These rollers are arranged substantially parallel to the shell and mounted on horizontal posts 27 and 28. The posts extend through the slot formed by the inner edges of the channel 23, and are each mounted on a flat plate 29 attached to the shell. Each corresponding pair of rollers 25 and 26 is aligned at substantially 45° with respect to the horizontal. The top roller 25 is at substantially the middle of the channel 23 when the roof is in its highest position, and is at the top of the channel when the roof is in its lowest position. The bottom roller 26 is at the bottom of the channel when the roof is in its highest position and at the middle of the channel when the roof is at its lowest position.

In order to prevent rotation of the roof as it rises and falls and to maintain a vertical path of travel for the roof there is provided a third roller 30 on the inner end of each horizontal bracket 14. These latter rollers are arranged flat and adjacent the shell, and are guided in vertical guide members. The vertical guide members for each roller 30 comprise a pair of angle irons 31 with one angle

iron on one side of the roller and the other angle iron on the other side of the roller. Each angle iron is arranged substantially vertically and has one edge attached to the shell and the other edge over the roller.

As the roof rises and falls the rotation of the roof is prevented by reason of the rollers 30 and their vertical guide members. The roof is maintained substantially horizontal at all times by means of the depending arms 16, polygonal structural member 21, and inclined elongated guide members 23.

Having described my invention as related to the embodiment set out in the accompanying drawings, it is my intention that the invention be not limited by any of the details of description unless otherwise specified, but rather be construed broadly within its spirit and scope as set out in the accompanying claims.

I claim:

1. In a lifter roof tank comprising a shell, a roof and a depending skirt therefrom, stabilizing and guide means comprising a plurality of substantially parallel depending arms all substantially equal in length rotatably attached at their upper ends to the depending skirt with each arm being pivotally attached at its lower end to the apex of a substantially horizontal member of polygonal shape extending around the shell but spaced therefrom, said lower ends of the depending arms being also attached to helical guides, all said helical guides being at substantially the same acute angle with respect to the horizontal and all extending in the same direction, and each helical guide always engaging at least two guide members on the shell wall and a separate vertical guide means between the roof and shell for preventing rotation of the roof as it rises and falls.

2. The stabilizing and guide means of claim 1 in which said helical guides are each arranged at substantially 45° with respect to the horizontal.

5. The stabilizing and guide means of claim 1 wherein the vertical guide means comprise a plurality of vertical guides with each of said guides attached to the roof above a helical guide, and a plurality of second guide members on the shell of the tank for guiding each of said vertical guides.

10. The stabilizing and guide means of claim 1 wherein the lower end of each arm is attached to a helical guide at substantially the center of said guide.

15. The stabilizing and guide means of claim 1 wherein the guide members for each helical guide comprise a pair of rollers attached to the shell with each roller being substantially parallel to the shell at its point of attachment and in which each helical guide is of channel cross-section surrounding the rollers, one of said rollers being substantially at the top and the other being substantially at the middle of its helical guide when the roof is in its lowest position.

20. The stabilizing and guide means of claim 1 wherein the guide members for each helical guide comprise a pair of rollers attached to the shell with each roller being substantially parallel to the shell at its point of attachment and in which each helical guide is of channel cross-section surrounding the rollers, one of said rollers being substantially at the top and the other being substantially at the middle of its helical guide when the roof is in its lowest position.

25. In a lifter roof tank comprising a shell, a roof and a depending skirt therefrom, stabilizing and guide means comprising a plurality of substantially parallel depending arms all substantially equal in length and rotatably attached at their upper ends to the depending skirt with each arm being pivotally attached at its lower end to a substantially horizontal member of annular shape extending around the shell but spaced therefrom, helical guides connected to the horizontal member, and guide members on the shell wall, all said helical guides being at substantially the same acute angle with respect to the horizontal and all extending in the same direction and each helical guide always engaging a guide member on the shell wall.

DONALD E. LARSON.
